UNITED STATES PATENT OFFICE.

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS.

FURNACE CONSTRUCTION.

Application filed August 26, 1926. Serial No. 131,578.

My invention relates to a furnace construction and particularly to a furnace for use with a hot air heating system. One object of the invention is the provision of improved air moistening means. Another object is increased efficiency in the transfer of heat from the furnace to the circulated air. Another object is the provision of means for protecting the head or top of the furnace from burning out. Other objects will appear from time to time in the course of the specification and claims.

I illustrate my invention more or less diagrammatically in the accompanying drawings, wherein:

Figure 1 is a vertical section; and

Figure 2 is a top plan view with parts omitted.

Like parts are indicated by like symbols throughout the specification and drawings.

A generally indicates the furnace proper, having a lower cylindrical portion A¹ and an upper tapered portion A². A³ is a concave head for the furnace surrounded by the rim A⁴ and in communication with a water supply pipe A⁵ controlled by any suitable float valve or level regulating means A⁶. A⁷ is the flue.

Any suitable burner may be employed with my furnace, whether for the combustion of solid, liquid or gaseous fuel, the details thereof forming no part of the present invention and not being herein shown. Positioned about the furnace is the outer housing B, herein shown as a cylinder concentric with the cylinder A¹. B¹ is an inwardly tapered portion adjacent the top thereof, and B² a smaller cylindrical portion thereabove.

Positioned intermediate the furnace A and the outer shell B is the wall C positioned for example by the spacers C¹ C². It preferably terminates at a level above the bottom of the furnace, or is so shaped or perforated as to permit a flow of air beneath or through its lower portion. It will be understood that in normal operation the cold air flows downwardly through the space between the members B and C and upwardly through the space between the members A and C.

In order to increase to a maximum the heating effect of the furnace upon the upwardly rising circulation of heated air and to prevent so far as possible the heating of the outer shell I provide a shield D spaced between the fire box zone of the furnace A

and the intermediate partition C. It may be made of dull finish in order to absorb a maximum heat and as the air circulates along the wall A¹ and between the furnace and the wall C it passes about said shield and absorbs the heat thereof. In order to increase the heating area thus provided the member D may if desired be corrugated.

In order to further concentrate the heat of the furnace upon the upwardly rising circulation of air the inner face of the wall C may be highly polished or tinned or painted with metallic paint in order to reflect back the heat radiated by the furnace.

It will be noted that the inward inclination of the wall A² of the furnace A decreases the cross-sectional area of the furnace and progressively increases the cross-sectional area of the heated air passage, from bottom to top of the furnace. This compensates for the contraction of the exhaust gases as they are cooled and the expansion of the air as it is heated.

It will be realized that whereas I have described and shown a practical and operative device, nevertheless many changes might be made in the size, shape, number and disposition of parts without departing from the spirit of my invention. I therefore wish my description and drawing to be taken as in a broad sense diagrammatic and illustrative rather than as limiting me to my specific showing.

The use and operation of my invention are as follows:

I have illustrated a furnace adaptable as a relatively small and ductless heating unit for heating rooms or small houses. It is preferably positioned beneath the floor level, the floor level in Figure 1 being indicated as X. Any suitable heating means being employed to raise the temperature of the furnace A to the proper degree, the air surrounding the furnace, namely in the space between A and C, will be heated by the furnace and will rise and pass upwardly into the room. The down-flowing cold air, on the other hand, will flow into the space between the walls B and C, and downwardly along and through or under the wall C adjacent the lower portion of the furnace A. There it rises and is re-heated by the furnace. The screen D absorbs a substantial proportion of the heat radiated by the furnace and this heat in turn is absorbed by the upwardly rising current of air.

The use of such screen, as well as the employment of a heat radiating inner surface for the wall C, limits to a minimum heat losses through the wall B and also limits the 5 risk of the overheating of adjacent partitions, if such there be, and consequent fire risks.

In order to humidify the air I provide a water holding top for the furnace. By so positioning the water reservoir I obtain an 10 adequate area of exposed water surface and at the same time eliminate the chance of burning out the furnace head. The water level may be regulated by any suitable manner and I do not wish to be limited to the float valve 15 herein shown.

I claim:

1. In a circulation heater adapted to be positioned beneath the floor level of the room to be heated, a furnace, an outer cylindrical 20 housing thereabout, a cylindrical partition intermediate said housing and said furnace, said partition terminating short of the bottom of the housing and being adapted to permit the downward circulation of air between 25 the partition and the furnace, the furnace being upwardly and inwardly tapered progressively away from the intermediate partition to increase progressively the cross-sectional area of the heated air passage formed 30 thereby, and an additional cylindrical shield member positioned between the partition and the fire box zone of the furnace and confined to the region below the tapered portion of the

furnace whereby a maximum quantity of air may contact directly with the furnace walls. 35

2. In a heating apparatus, a furnace, a housing therefor, a partition positioned between the furnace and the housing and defining concentric air conduits, a heat-absorbing shield positioned between the partition 40 and the furnace and confined to the fire box zone of the furnace and serving to insulate the lower portion of the partition from direct radiations from the furnace walls, the partition above the shield being subject to direct 45 radiations from the upper walls of the furnace and being provided with a bright, heat-reflecting surface.

3. In a heating apparatus including a furnace surrounded by a partition on the opposite sides of which air flows in reverse directions under the influence of heat from the furnace walls, the combination of a narrow heat-absorbing shield surrounding the fire box 50 zone of the furnace and positioned between the furnace and said partition to insulate the partition from direct radiations from the fire box zone of the furnace, said partition 55 extending above the shield and being provided with a bright, heat-reflecting surface 60 subject to direct radiations from the furnace walls.

Signed at Chicago, county of Cook and State of Illinois, this 23d day of August, 1926.

JAMES L. BREESE, JR.
